POWER-OPERATED IMPACT WRENCH

Frederic T. Hamlin, Stewartsville, N. J., assignor
to Ingersoll-Rand Company, New York, N. Y.,
a corporation of New Jersey

Application October 9, 1948, Serial No. 53,620

5 Claims. (Cl. 81—52.3)

1

This invention relates to impact wrenches and more particularly to wrenches utilized to rotate relatively large nuts, as for example, around 5 inches outside diameter.

Heretofore, in order to tighten or loosen nuts of the size referred to, it was necessary to resort to the wrench sledge hammer method or, in lieu of a sledge hammer, a ram supported from the ceiling by cables or ropes and swung back and forth by two or more men was used to hammer the wrench. Such an arrangement has several obvious disadvantages, other than its inefficiency—as for example, the high linear stresses developed in the bolt on which the nut is being tightened. It is, accordingly, one object of my invention to develop torque free of linear stresses for tightening nuts and bolts and the like.

Another object of my invention is to utilize the rotational energy of a body, relatively massive compared to the body to be rotated, in a device of the character referred to.

A further object of my invention is to construct an impact wrench in such a manner that the driving force or prime mover for the wrench is not subject to undue strain at the instant of impact of the wrench.

Other objects will become obvious hereinafter.

In the drawing accompanying the specification and in which similar reference characters refer to similar parts,

Figure 1 is a vertical elevation, partly in section, of an impact wrench constructed in accordance with the practice of the invention,

Figure 2 is a top view, partly in section, of the impact wrench arranged to rotate a body in the clockwise direction.

Figure 3 is a top view of the impact wrench arranged to rotate a body in the counterclockwise direction, and

Figure 4 is a vertical elevation, partly in section, of the clutch arrangement for the impact wrench for obtaining counterclockwise rotation of the body to be rotated.

Referring to the drawing and more particularly to Figure 1, 10 designates, in general, a preferred form of the impact wrench supported in its operative position for tightening a nut 11 on a bolt 12 by a cradle 19 which in turn is supported by cables 20 depending from an overhead construction (not shown). In the main, the wrench 10 comprises a torque producing member or wheel 13 of relatively massive size, compared to the nut 11, rotated by an air motor 14 slidably mounted on a wrench member 15 which intermittently engages the wheel 13 to transmit

2

torque therefrom to the nut 11. To this end, the wrench member 15 at one end grips the nut 11 and is provided on the other, or opposite, end with a pair of cams 16 having engaging faces 17 spaced 180 degrees apart and positioned coaxially with a similar pair of cams 18 on the wheel 13 for engagement therewith.

More specifically, the cradle 19 comprises a horizontally disposed plate 21 having radial arms 22, in this instance three, of such a length that the vertically extended ribs 23 mounted on the ends of the arms 22 clear the periphery of the wheel 13 mounted in a horizontal position above the plate 21, and it is to these ribs 23 that the cables 20 are secured by means of eye bolts 24 threaded in the upper ends of said ribs. Encircling a central perforation 25 in the plate 21 through which loosely extends the wrench member 15, is a groove 26 of slightly greater diameter than a flared portion or flange 27 on the member 15 which rests therein. With this arrangement, the wrench member 15 is permitted to rotate freely relative to the cradle 19, and the groove 26 serves to maintain proper alignment between the wrench member 15 and the nut 11.

Slidably mounted in a groove 28 in the periphery of the flange 27 is a support 29 for the air motor 14 which serves as a means for rotating the torque producing member, or wheel 13, and is accordingly provided with a driving connection, such as the gear 30 keyed to the motor shaft 31, which engages gear teeth 32 on the rim of the wheel 13. In the preferred form of the invention, the motor 14 is designed to reach its maximum speed, from rest, in the time required to rotate the wheel 13 180 degrees. Thus, the wheel 13 reaches its maximum speed at the instant the cams 18 engage the cams 16.

In order to prevent the motor 14 from walking, or propelling itself, around the wheel 13 when the wheel is engaged with the wrench member 15, or otherwise prevented from rotating, a yieldable means, such as the spring 33, is connected between the arms 34 and 35 mounted, respectively, on the wrench member 15 and the support 29. Thus, any tendency of the motor to move relative to the wheel 13 is resisted by the nut through the member 15—that is, rotation in this direction would tend to unscrew the nut 11. This arrangement requires, of course, that nut 11 be initially tightened enough to resist this unscrewing action. The spring 33 serves, further, to reduce the shock to which the motor 14 is subject at the instant of impact of the mat-

ing of cams 16 and 18, resulting from the tendency of the wrench member 15 to rotate the motor support 29. However, due to the floating or sliding relation between the wrench member 15 and the motor support 29, at impact the spring 33 will stretch and permit the motor, as a whole, to reach an equilibrium position without rotating, relative to the bolt 12 or other stationary objects, at the high speed imparted to the member 15 by the wheel 13. The equilibrium position is, of course, dependent on the strength of the spring 33 and the power of the motor—that is, whenever the wheel 13 is held against rotation and the motor is supplied with power, the motor tends to travel around the wheel 13 and thereby stretch the spring 33 until the motor stalls.

As previously mentioned, the motor 14 is, in this instance, air driven and is accordingly supplied with a motive fluid or air by means of the conduit 36 from a source (not shown). A branch 37 of the conduit 36 passes through a three-way valve 38, which, for the sake of simplicity, is shown as being manually operated, and thence to the member 15 for supplying motive fluid to the wrench for disengaging the cams 16 and 18. To this end, the wrench member 15 is provided with a central bore 39 into which extends a rod or piston member 40 mounted coaxially on the wheel 13 and having a pressure surface 44 on the lower end thereof exposed to the motive fluid delivered to the lower end of the bore 39 by the conduit 37. Thus, whenever the three-way valve 38 is positioned to allow motive fluid to flow to the bore 39, the torque producing member 13 will be moved vertically along its axis and thereby disengage the cams 16 and 18. The upward movement of the wheel 13 is limited by an exhaust port 41 for the bore 39 and positioned in such wise as to permit the cams 16 and 18 to clear each other before the pressure fluid is exhausted from the bore 39. Reverse longitudinal, or downward, movement of the wheel 13 is attained by either exhausting the pressure fluid from the bore 39 through the valve 38 or by cutting off the pressure supply to the bore 39 by means of the valve 38 and permitting the air in the bore 39 to leak past the piston rod 40 and escape through the port 41 thereby permitting the weight of the wheel, or gravitational force, to move the wheel 13 into a position to align the cams 16 and 18.

Proper alignment between the wrench member 15 and the wheel 13 during disengagement of the cams 16 and 18 is maintained by providing a groove 42 in the hub of the wheel 13 and encircling the piston member 40, into which fits a sleeve 43 extending from the axis of the member 15. The length of the sleeve 43 is of such dimension as to permit the sleeve 43 to remain in contact with the inner surface of the cams 18 at all times, and the groove 42 is of such a depth as to permit the mating faces on the cams 16 and 18 to be in full engagement at the instant of impact.

When reverse rotation of the nut is desired, it is merely necessary to replace the wrench member 15 with the wrench member 45 (shown in Figure 4) having oppositely disposed cams 46 relative to the cams 16; mount the spring 33 and associated arms 34 and 35 on the opposite side of the motor 14, in that direction of rotation of the motor and wheel 13 are reversed; and turn over the wheel 13 so that the cams 47 provided for this purpose on the opposite side

of the wheel and having oppositely disposed mating faces, relative to the cams 18, engage with the cams 46. There is, of course, a piston member 40 provided on the same side of the wheel 13 as the cams 47, for imparting longitudinal movement to the wheel 13 for disengaging the clutch or cams 46 and 47. A protective cap 48 is provided which fits over either of the members 40 and is secured thereto by bolts or screws 49 threaded through the cap 48 and extending into a groove 50 in the periphery of the member 40. This cap serves to protect the end or pressure surface of the member 40 from possible damage from an external source during the period it is not in use, i. e., when it is not inserted in the bore 39.

In operation, assuming clockwise rotation (as viewed in Fig. 2) of the wheel 13, air is valved to the motor 14 which immediately moves around the periphery of the wheel 13 until the tension of the spring 33 is sufficient to stall the motor. The operator then shifts the three-way valve 38 to permit motive fluid to flow into the bore 39 to disengage the cams 16 and 18, in the manner previously described. When the cams 16 clear the cams 18, the three-way valve 38 is placed in position, by the operator, to exhaust fluid from the bore 39 to permit the wheel 13 to slide into its mating position as it is rotated by the motor 14. At the instant of impact, the wrench member 15 is fully engaged or clutched to the wheel 13 and the kinetic or rotational energy of the wheel is dissipated in turning the nut 11 against frictional resistance. The above cycle is then repeated until the desired tightness of the nut is attained.

It is now obvious from the previous discussion that an impact wrench constructed in accordance with the practice of the invention provides a relatively simple yet highly effective means for tightening nuts and bolts and the like and which may readily be adapted for loosening the same and, further, in both instances, torque is developed that is relatively free of linear forces. Still further, such a mechanism is provided with a means for preventing undue strain in any of its parts and more particularly to the prime mover at the instant of impact of the cams or other clutch arrangement.

While I have shown and described a specific form of my invention, it is to be understood that various changes and modifications may be made without departing from the spirit of the invention as set forth in the appended claims.

I claim:

1. An impact wrench comprising, a torque producing member, means for rotating said member, means engaging the torque producing member for transmitting rotary movement therefrom to the member to be rotated, means for disengaging the first said member from the second said means, a support for the first said means slidably mounted on the second said means, and yieldable means for limiting relative movement between the support and the second said means.

2. An impact wrench comprising, a wheel shaped torque producing member, a motor for rotating said torque producing member, a driving connection between the motor and the periphery of said member, means engaging said torque producing member for transmitting torque therefrom to the member to be rotated and having a chamber therein, means attached to the first said member extending into said chamber and having a pressure surface on the end there-

of, and means for conveying pressure fluid to said pressure surface.

3. An impact wrench comprising, a wheel shaped torque producing member, a motor for rotating said member, a driving connection between the motor and said member, a wrench coaxial with said member for transmitting torque therefrom to the member to be rotated and having a central bore, cams on the remote end of said wrench, cams on the first said member engaging the first said cams, a rod attached to the first said member and extending slidably into said bore, and means for imparting longitudinal movement to said rod for disengaging said cams.

4. An impact wrench comprising, a wrench member having a bore, a wheel shaped member horizontally mounted on said wrench member and of relatively massive size compared to the member to be rotated, cams on an end of the wrench member, oppositely disposed cams on the wheel engaging the first said cams, a support rotatably mounted on said wrench member, a motor mounted on the support for rotating said wheel shaped member, and yieldable means connected between said support and said wrench member.

5. An impact wrench comprising, a torque producing member, a wrench adapted to be periodi-

cally engaged by such member for transmitting a rotational force to a member to be rotated, a motor slidably mounted on said wrench and provided with means to engage and rotate the torque producing member, and yieldable means yieldably connecting said wrench to said motor for limiting rotational movement of the motor relative to the torque producing member and to limit the shock transmitted to the motor from said wrench on impact of said torque producing member with the wrench.
